Carl Schevitz

INVENTOR
Victor J. Evans

ATTORNEY

UNITED STATES PATENT OFFICE.

CARL SCHEVITZ, OF JACKSONVILLE, FLORIDA.

EXPANSIBLE SHOE LAST.

Application filed February 21, 1921. Serial No. 446,654.

To all whom it may concern:

Be it known that I, CARL SCHEVITZ, a citizen of the United States, residing at Jacksonville, in the county of Duval and

5 State of Florida, have invented new and useful Improvements in Expansible Shoe Lasts, of which the following is a specification.

This invention relates to shoe stretching means, the present invention being an im-

10 provement over that forming the subject matter of a patent granted to me on May 24, 1921, No. 1,379,478.

The principal object of the present invention is to improve and simplify the construction of the device so that it will be more effective in operation and can be manufactured at less cost.

Another object of the invention is to provide actuating means for adjusting the position of the heel member, with means for locking it in adjusted position.

A further object of the invention is to provide means for shifting the instep stretching member bodily so that said member can be moved against the instep of the shoe to stretch the same.

Another object of the invention is to provide means whereby the side stretching member can be forced outwardly quite a distance from the side of the frame.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device.

Figure 2 is a similar view with one of the enclosing plates removed.

Figure 3 is a plan view of the device.

Figure 4 is a view partly in section of one of the side stretching members.

Figure 5 is a like view of a modified form 50 of stretching member.

Figure 6 is a perspective view of one of the adjusting members for the side stretching member.

Figure 7 is a perspective view of the companion member.

Figure 8 is a perspective view of one of

the rocking members for the side stretching member actuating means and showing how it is connected with the screw actuating shaft.

Figure 9 is a perspective view of the inner frame.

Figure 10 is a perspective view of the rocking member for the instep stretching device.

Figure 11 is a view of the actuating shaft for said rocking lever.

Figure 12 is a view of the key for operating the parts.

Figure 13 is a rear view with the heel plate removed.

Figures 14 and 15 are detail views.

In these views 1 indicates the main frame which is provided with the intermediate contracted portion 1' for fitting in the shank 75 of the shoe. The side bars of the frame are provided with the slots 2 and the rear of the frame is secured to the lower end of the upright 3, the major portion of this upright being of channel shape in cross section and 80 the front part of the main frame is provided with horizontal flanges 4 at its upper edges for a purpose to be hereinafter described. Within the main frame is arranged an inner frame 5 which consists of a pair of 85 longitudinally extending spaced strips 6 having their rear portions extending upwardly, as at 7 and their rear extremities connected together, as at 8. The frame also comprises the bottom flanges 9 and the upper flanges 10 which are bent outwardly 90 from the front parts of the strips 6. Extensions 11 are formed on the front ends of the strips 6 for engaging holes formed in the front end of the main frame. The 95 flanges 9 form a bottom for the device and flanges 10 cooperate with the flanges 4 of the main frame and said flanges 9 for forming guideways for the actuating members of the side stretching parts. The strips 6 and extensions 7 form a guideway for the longitudinally movable bar 12 which passes through the opening in the front cross piece of the main frame and is provided with a spring pressed pin 13 for holding the toe 100 stretching member 14 upon the front end of this bar. The rear end of this bar is provided with a screw threaded bore which receives the screw threaded part of shaft 15, said shaft 15 is connected with the upright shaft 16 by the gears 17. Shaft 16 is 105 carried by lugs 18 extending outwardly from

the upright 3. The upper end of the shaft 16 is squared to receive the square socket in key 19. The toe stretching member and its actuating parts are similar to those described in the before mentioned patent.

The means for actuating the side stretching members 20 consists of a rack member 21 and a companion member 22 arranged on each side of the inner frame and slidably supported in the guideway formed by flanges 9 and 10. Each of the members 21 and 22 is provided with a rightangularly bent end 23 extending across the guideway and engaging the flanges. Member 22 is provided with a short flat part 24 for engaging the long flat part 25 of member 21 and said member 22 has its major portion offset laterally so that this part is spaced from member 21 to provide a space for receiving the lower end 20 of the rocker arm 26 and this rocker arm is pivotally secured to member 22. Each rocker arm 26 is pivotally and movably connected with the upwardly curved portions 27 of the main frame by means of the pin 28 on the rocker arm engaging the arc-shaped slot 29 in the part 27. The upper end of each rocker arm 26 is pivotally secured to a bracket 30 which is provided with a socket for receiving the lower end of a screw threaded shaft 31 which passes through the stationary nut 32 on the horizontal part 33 of the upright 3. The brackets 30 are provided with straight rear edges for engaging one face of the upright 3 so that this upright acts as a guiding member for the bracket. The rack carrying part 34 of member 21 is connected with the reduced part 35 by the rightangular part 36 and this part 35 is slightly offset from the part 25. Thus the rack part 34 is located quite a distance above the main frame. A laterally extending lug 37 is formed on the rear end of part 25 and is adapted to be engaged by a part of the rocker arm when the side actuating means for the side stretching members are being retracted so that both of said members 21 and 22 will be moved rearwardly. The part 34 of each member 21 passes through a slot formed in the upright and a vertically movable plate 38, engaging the rear face of the upright, is formed with extensions at its side edges for engaging the teeth on said parts 34 of the members 21 to lock said members in adjusted position. The upper end of this plate extends through a slot in the upper part of the upright, said slot being formed with a wide portion and a narrow portion and the plate having a shoulder so that said plate can be held in its upper position by placing the shoulder in engagement with the walls of the narrow part of the slot to hold the plate out of engagement with the teeth of members 21 so that said members can be moved freely. A spring 39 tends to hold the

plate in its lowest position with its side extensions in engagement with the teeth. This arrangement of parts is somewhat similar to that described in the before mentioned patent.

It will be seen that when the screw threaded shaft 31 is rotated by means of the key 19 the rocker arm 26 will be moved bodily and at the same time rocked upon its pivot so that the member 22 will be moved longitudinally. Thus member 22 will move along member 21 until its bent end causes the projection on the side member 20 to act on the end 23 of member 21 when said member 21 will be carried along with the member 22. On the reverse movement of the parts the member 22 will slide on member 21 until the lug 37 is engaged by the rocker arm 26 and then said member 21 will move with the member 22. The projection on the side stretching member 20 is adapted to be placed through the slot 2 in the main frame and between the bent ends 23 of members 21 and 22. Thus the side member will be moved with the said members 21 and 22 and then by lowering the locking plate 38 into engagement with the teeth on part 34 said member 21 will be prevented from movement while member 22 continues to move and thus forces the side member laterally to stretch the shoe. This side member may be provided with the cam projection shown in the before mentioned application but I prefer to use the toggle lever arrangement, shown at 40, the projecting ends 41 of which are adapted to be placed between the bent ends 23 of the members 21 and 22. Thus when the member 21 is held stationary and the member 22 moved the ends 24 will be brought together so as to expand the toggle levers and thus move the stretching member outwardly to stretch the shoe.

In Figure 5 I show a modification in which the ends of the toggle levers are pivotally secured to the ends 23, as at 42. This view also shows the side stretching member 20' as receiving a cover 20'' which may be formed to stretch the side of the shoe to make the shoe conform to the bunion or other deformity on the foot, these covers being made of various shapes and are detachably connected with the member 20', as shown. The parts are so arranged in both forms of the invention that the side stretching member can be adjusted to its proper position in the shoe by moving both members 21 and 22 and then by locking member 21 against movement and moving the other member the toggle levers will be expanded to force the stretcher member outwardly to expand the shoe.

The rear end of the inner frame 5 is provided with a bent tongue 43 which passes through an opening in the upright and acts as a guide for the lower end of the vertically

movable plate 38. This tongue also provides a shoulder 44 for engagement by a projection 45 on the rock bar 46 which actuates the instep stretching member 47. This bar 46 is pivoted between the portions 7 of the inner frame and has an eye 46' at its front end for receiving the pivot pin which pivots it to the said instep stretching member 47. The rear end of the arm is enlarged, as at 10 48, and the upper edge of this enlargement is provided with a groove 49 for receiving the rounded end of the screw shaft 50. This screw shaft is mounted in the upright and is adapted to be actuated by the key 19. 15 Thus when the said shaft is lowered its rounded end striking the bottom of the groove 49 will depress the rear end of arm 46 and raise the front end and thus press the member 47 against the instep of the 20 shoe. The parts will return to normal position by gravity when the shaft 50 is raised. The upward movement of the instep member is limited by the projection 45 striking the shoulder 44. It will be seen that the 25 instep member is moved bodily so that the entire front portion of the instep of the shoe is stretched.

The heel frame 51 is of substantially U-shape in cross section and is provided with 30 the forwardly projection rack arms 52 which pass through slots in the upright and engage the upper edges of the main frame and the outer sides of the portions 27, these parts acting as guides for the arms. A pair of 35 levers 53 are pivotally mounted to the upright, as at 54, with their lower ends reduced and passing through slots in lugs 55 carried by the lower part of the heel frame. These levers have a limited movement in the 40 slots of the lugs so that the levers will move to a certain extent before the movement is communicated to the heel frame. The upper ends of the levers are bent at right angles from the pivotal point and a handle supporting member 56 is pivotally mounted between these ends by the pivot pin 57. These ends are provided with arc-shaped slots 58 through which passes a bolt 59' which is carried by the part 56. The handle 59 is 45 connected with the part 56 by a pin and slot connection 60 and said handle having a notch 61 therein for engaging the pin 57. This arrangement of parts permits the handle to be moved into inoperative position as shown in Figures 1 and 2 or into 50 operative position where it can be used to move the heel frame.

The heel plate is locked in adjusted position by means of the pawl carrying plate 62 60 which is slidably arranged at the rear of the upright and is provided with the outwardly extending ears 63 provided with holes through which passes the shaft 16. A spring 64 mounted on said shaft tends to 65 hold the plate with its pawls in engage-

ment with the teeth of arms 52. A link 65 pivotally connected with member 56 by the bolt 59' has its lower end hooked and passes through a slot in one of the ears 63 so that when said member 56 is rocked by the handle member the link will be moved longitudinally so that its hooked end engaging the lug 63 will raise the plate 62 out of engagement with the rack arms 52 so as to permit the heel frame to be moved on the further movement of the handle, this movement being communicated to the heel frame by the levers 53.

The parts are enclosed by the side plates 65' and the bottom of the device is covered by a plate 66 which has an ear 67 at its front end passing through the hole in the front end of the main frame and an ear 68 at its rear end which engages a plate 69 forming a bottom for the heel frame, when the same is closed, said plates 65' and 69 having ears 70 which are bolted to the rear end of the main frame by the same bolts which connect the main frame with the upright.

The operation of the device is substantially the same as that of the device forming the subject matter of the before mentioned patent.

The device is placed within the shoe with the heel frame in closed position and the other parts in contracted position. The heel frame is then adjusted by the handle 59 and its associated parts to make the device fit snugly in the shoe. The key 19, which is provided with a crank handle 19' is then placed on the shaft 16 to force the toe stretching member 14 into the toe to stretch the same. The key is then placed on shaft 50 to rock arm 46 to adjust the instep member 47 to stretch the instep of the shoe. Then the key is placed on one of the shafts 31 to adjust the side stretching member to the desired position after which the plate 38 is lowered to lock the member 21 against movement and then shaft 31 is rotated to cause the member 22 to force outwardly the side stretching member to stretch the side of the shoe.

As will be seen either side of the shoe may be stretched or both sides by placing a side stretching member at each side of the shoe.

All the operations are carried out from the exterior of the shoe so that it is not necessary to place the hands within the shoe.

The side plates and the bottom plate will give the device the appearance of an ordinary last and at the same time protect the working parts from dust and dirt.

What I claim is:

1. A shoe last of the class described comprising a main frame, a heel frame, a rack bar connected with the heel frame and slidably supported in the main frame, a ratchet plate engaging said rack bar, a lever piv-

stally supported on the main frame and connected with the heel frame, a handle for rocking the lever for moving the heel frame and means connecting the handle with the plate for lifting said plate out of engagement with the rack bar when the handle is manipulated to move the heel frame inwardly.

2. A shoe last of the class described comprising a main frame, a rocker arm pivotally mounted thereon intermediate its ends, an instep stretching plate pivotally connected to one end of the rocker arm, the other end of the rocker arm being enlarged and having its upper edge curved and grooved, means for limiting the downward movement of the enlarged end of the arm, a longitudinally movable shaft in the main frame having its end engaging the groove and a key for actuating the shaft.

3. A shoe last of the class described comprising a main frame, a side stretching member, expansible levers connected therewith and means carried by the main frame for adjusting the side stretching member longitudinally of the main frame and for actuating the expansible levers to move said side stretching member laterally.

4. A shoe last of the class described comprising a main frame, a side stretching member, expansible levers connected therewith, means carried by the frame for actuating said expansible levers to move the side stretching member laterally and a detachable cover for the side stretching member.

5. A shoe last of the class described comprising a main frame, a side stretching member, a pair of jaw members slidably mounted in the main frame and engaging the side stretching member, each jaw member consisting of a bar having one end bent at an angle to form the jaw, a projection on one jaw member for engaging the other member to cause the first member to move rearwardly with the second member after said second member has moved a certain distance, a pivotally and movably supported rocker arm connected with the second jaw member and means for actuating the rocking lever.

6. A shoe last of the class described comprising a main frame, a side stretching member, a pair of jaw members slidably mounted in the main frame and engaging the side stretching member, each jaw member consisting of a bar having one end bent

at an angle to form the jaw, a projection on one jaw member for engaging the other member to cause the first member to move rearwardly with the second member after said second member has moved a certain distance, a pivotally and movably supported rocker arm connected with the second jaw member, means for actuating the rocking lever, and locking means associated with the second jaw member to hold said member against movement.

7. A shoe last of the class described comprising a main frame, a side stretching member, a pair of jaw members slidably mounted in the main frame and engaging the side stretching member, each jaw member consisting of a bar having one end bent at an angle to form the jaw, a projection on one jaw member for engaging the other member to cause the first member to move rearwardly with the second member after said second member has moved a certain distance, a pivotally and movably supported rocker arm connected with the second jaw member, means for actuating the rocking lever, locking means associated with the second jaw member to hold said member against movement, such locking means consisting of a rack on the jaw member and a locking member having a part engaging said rack.

8. A shoe last of the class described comprising a main frame consisting of an outer frame and an inner frame, said frames providing a central guideway and a pair of outer guideways, a longitudinally movable bar in the inner guideway, a toe stretching member connected with said bar, means for actuating said bar, a pair of jaw members in each of the outer guideways, each jaw member consisting of a bar having one end bent to form the jaw, the side pieces of the outer frame having slots therein, a side stretching member having parts adapted to pass through the slots and to be engaged by the jaws, means for actuating the jaw members, such means including means for moving one jaw member while the other is stationary and for moving both the jaw members in unison when the stationary member is unlocked, locking means for said stationary member, a rocker arm pivotally supported by the inner frame, an instep stretching member carried by said rocker arm and means for actuating said arm.

In testimony whereof I affix my signature.
CARL SCHEVITZ.
